UNITED STATES PATENT OFFICE.

HENRY KERSHAW, OF INDIANAPOLIS, INDIANA.

VACUUM LIQUID-SUPPLY APPARATUS.

Application filed October 27, 1921. Serial No. 510,928.

To all whom it may concern:

Be it known that I, HENRY KERSHAW, a citizen of the United States, residing at Indianapolis, in the county of Marion and State of Indiana, have invented new and useful Improvements in Vacuum Liquid-Supply Apparatus, of which the following is a specification.

This invention relates to vacuum controlled fuel feeding apparatus for motor-vehicle engines, whereby the liquid fuel is drawn from a low level supply to an elevated receptacle and then permitted to flow from the latter by gravity to the carburetor of the engine.

The invention has for its object to provide in an apparatus of the kind stated a novel and improved structure and mode of operation as will be described and detail 20 hereinafter, and in order that the same may be better understood, reference is had to the accompanying drawing, wherein:

Figure 1 is a vertical section of a receptacle showing the valve mechanism contained therein; Fig. 2 is a similar view showing a different position of a valve mechanism, and Fig. 3 is an edge view of certain parts associated with the valve mechanism.

As is well understood in the art, the vacuum feed system employs a tank shown at 5 in the drawing, said tank being divided into upper and lower chambers 6 and 7. The upper chamber is connected to the intake manifold of the engine by a suitable pipe 8, so that when in operation, the suction produced by the engine creates a partial vacuum in the chamber, whereby liquid fuel is drawn in through a pipe 9 leading from a low level supply. The partition 10 which divides the tank into the two chambers has an outlet 11 into the lower chamber, the same being provided with a check-valve as usual. The bottom of the tank has an outlet 12 to which is connected a pipe (not shown) which delivers the fuel from chamber 7 to the carburetor by gravity.

In the upper chamber 6 is a float 13 which operates in conjunction with a valve for controlling the entry of fuel into said chamber. This valve mechanism is designed and arranged to open the chamber 6 to the external atmosphere, and when this occurs, it will be obvious that there is not enough suction in the chamber to draw fuel thereinto and

hence the flow of fuel is interrupted. As the fuel continues to flow from chamber 6 into chamber 7, the lowering fuel level in the former causes the float 13 to go down, and when a predetermined low level is reached, 60 the float, through certain connections to be presently described, closes the valve, whereupon the suction through pipe 8 again establishes a partial vacuum in the chamber 6, and the flow of fuel thereinto from the 65 source of supply is resumed.

The valve referred to is shown at 14 in Fig. 2. The top 15 of the tank 5 has an air vent port 16 which is controlled by the valve, said valve moving downwardly to closing 76 position. The port 16 leads to a passage 17 which opens into the external atmosphere, said passage being made in a thickened portion 18 of the tank top 15. The part 18 also has a hollow upward extension 19 at one end 75 into which the valve 14 moves upwardly when it opens, as shown in Fig. 2. The part 19 is closed by a screw plug 20 the inner end of which also serves to limit the upward travel of the valve 14.

The valve 14 has a depending stem 21 which extends through port 16 into the chamber 6, and works in a guide 22 carried by the tank top 15.

From the tank top 15 also depend two laterally spaced bracket arms 23 between which seats and is pivoted, as shown at 24, a lever 25 having one end connected to a suitable fitting 26 secured to the top of the float 13. To the other end of the lever, this end being 90 forked, is pivoted as shown at 27, between the fork branches, one end of a link 28, said link extending upwardly and having its other end connected to a lever 29 which is pivoted, as shown at 30, between the bracket 95 arms 23. One end of the lever 29 is forked and carries a cross pin 31 which passes through a slot 32 in link 28, whereby a loose or sliding connection is made between said lever and link. The other end of lever 29 100 is also forked to straddle the valve stem 21 between two vertically spaced collars or other abutments 33 thereon, whereby the motion of the lever is transmitted to the valve stem.

By the hereinbefore described connections, the lowering of the float 13 to a predetermined level causes valve 14 to close, whereas when the float rises to a certain predetermined height, the valve opens. Fig. 2 shows 110

the float 13 at the limit of its upward travel, the valve 14 having been opened. When the float goes down the end of lever 25 to which the link 28 is connected swings upwardly toward the end of lever 29 to which the link is also connected, and when the predetermined downward travel of the float has been reached the lever 25 engages the lever 29 and swings the latter to the position shown in Fig. 1, thereby pulling the stem 21 down and closing valve 14. The link 28 of course goes up with the lever 25, so that the cross pin 31 is now near the upper end of the link slot 32. As the float goes up the lever 25 swings away from lever 29 and draws link 28 down, and when the float reaches the limit of its upward movement the upper end of link slot 32 engages pin 31 and swings lever 29 to push valve stem 21 upwardly and move the valve 14 to open position, as shown in Fig. 2.

It will be noted that the end of the lever 29 to which the link 28 is connected is made heavier than the end which is connected to the stem 21 of the valve 14, so that the lever acts as a counterbalance, and has a normal tendency to swing in a direction to open the valve. However, when the valve is closed, the vacuum or suction in the chamber 6 tends to hold it closed until the float 13 rises and draws the link 28 down far enough to bring the upper end of the slot 32 in contact with the cross pin 31, whereupon the valve is lifted slightly off its seat. This relieves the valve of the suction tending to hold it closed, and the weighted end of lever 29 now swings down to push the valve wide open to completely destroy the vacuum in the chamber 6. Thus no further fuel can be drawn into the latter. If the motor should stop when the float has risen but partially, a cessation of the suction would ensue, whereupon the weighted end of the lever 29 would cause the same to swing in a direction to open the valve 14. This would completely relieve the vacuum and no further action would take place until the motor is again started, and its suction draws the valve into closed position.

If the motor should stop while the float is still down, it is safe to assume that, with

the present mechanism in good order, the stopping was due to faulty ignition or some extraneous cause. Hence, with the fault remedied, there should be sufficient fuel in the carburetor to enable the engine to start, causing, with the parts positioned per Fig. 1, a new supply of fuel to be drawn into the chamber 6 for delivery to the carburetor.

The mechanism does not require the use of a spring and it does not violently jerk the valve 14 open or closed. Wear of all the parts is therefore reduced to a minimum, and it is also possible to use almost any metal in the construction of the valve seat. The apparatus feeds steady under all conditions, and it does not affect the even running of the motor.

I claim:

1. In a vacuum liquid supply apparatus, a vacuum chamber having an air-vent port, a valve controlling said port, a lever having an operative connection at one end with the valve, a link having a sliding connection at one end with the other end of the lever, a second lever connected at one end to the other end of the link, and a float connected to the other end of the second lever.

2. In a vacuum liquid supply apparatus, a vacuum chamber having an air-vent port, a valve controlling said port, a lever having an operative connection at one end with the valve, a link having a sliding connection at one end with the other end of the lever, a second lever connected at one end to the other end of the link, said end of the second lever being positioned to engage the end of the first-mentioned lever to which the link is connected, and a float connected to the other end of the second lever.

3. In a vacuum liquid supply apparatus, a vacuum chamber having an air-vent port, a valve controlling said port, a lever having an operative connection at one end with the valve, a link having a sliding connection at one end with the other end of the lever, said lever end being weighted, a second lever connected at one end to the other end of the link, and a float connected to the other end of the second lever.

In testimony whereof I affix my signature.

HENRY KERSHAW.
